UNITED STATES PATENT OFFICE.

McCLINTOCK YOUNG, OF FREDERICK, MARYLAND.

BRUSH.

SPECIFICATION forming part of Letters Patent No. 447,996, dated March 10, 1891.

Application filed June 26, 1890. Serial No. 356,849. (No model.)

To all whom it may concern.

Be it known that I, MCCLINTOCK YOUNG, of Frederick, in the county of Frederick and State of Maryland, have invented certain Improvements in Brushes, of which the following is a specification.

This invention has reference more particularly to that class of brushes represented in Letters Patent of the United States No. 423,506, granted to me on the 18th day of March, 1890, in which metallic fasteners are driven into the face of a brush-block in such form and manner that each fastening serves to retain a series of tufts in holes bored in the block or body.

The object of the present invention is to reduce the cost of the fastening devices and to admit of their being the more firmly secured in position; and to this end it consists, essentially, in a sinuous or serpentine fastening, preferably formed of wire, with a series of teeth or projections adapted to extend down within the tuft-receiving holes.

Referring to the drawings, Figure 1 represents my improved fastening in its preferred form. Fig. 2 is a perspective view of a portion of the brush with one end shown in cross-section through a row of tufts to expose the fastenings to view. Fig. 3 is a longitudinal section through the brush on the line 3 3 of Fig. 2. Fig. 4 is a face view of a portion of a brush-body with my fastening applied thereto, the tufts being omitted in order that the position of the fastener may be plainly shown.

Referring to the drawings, A represents a brush block or body, preferably consisting of a single block of wood having in its face a series of holes a, arranged in rows, and each adapted to receive a folded or doubled tuft B in the ordinary manner.

C represents a fastening device consisting of a wire or slender metallic strip bent to and fro in such manner as to produce a series of U-shaped portions c, connected at their upper ends by intermediate portions c'. The portions c are adapted each to extend down into one of the tuft-receiving holes within the bight or fold of the tuft to hold the latter down to its place within the body. In order that they may the more firmly hold the tufts

and to prevent the tufts from working outward from under them, the portions c are preferably made concave at the lower end in order to straddle or embrace the tufts, as shown in the drawings. The upper portions c' are adapted to span the upper edge of the wall or portion of the block between the adjacent tuft-holes.

In making use of the device its series of projections c are driven downward tightly into the adjacent holes in the line of tufts, as plainly shown in Figs. 2, 3, and 4.

In inserting the fastener I prefer to seat its vertical arms firmly against or within the side walls of the holes, and in order that the fastener may be held the more firmly in position I propose to provide the vertical arms with teeth or serrations c² to engage the wood.

While the fastener may be punched or cut from sheet metal, I find it advisable for many reasons to construct it of wire, which is accomplished by taking a single piece of wire of suitable length and diameter, preferably steel wire of moderate temper, and bending the same into the required form. As these portions which enter the tuft-holes, and which may be considered individual fasteners, are connected by the portions c, the fastener serves to tie the block together laterally, and in the event of the portion which holds one tooth failing to take a firm hold in the body it will nevertheless be retained in position through its connection with the adjacent portions.

One of the advantages of the present construction lies in the fact that spaces c⁴, which exist between the top connecting portions c', permit the two sides of the tuft to close compactly together, so that the exposed portion of the tuft presents a close compact body of fibers or bristles. In this regard the fastening is superior to the one represented in my patent above referred to.

Having thus described my invention, what I claim is—

1. A fastener for securing tufts in series in a brush-block, consisting of a narrow sinuous strip presenting on one edge the projections to enter the tuft-holes and bear within the bight of the tufts and on the other edge the

notches or openings whereby the two sides of each tuft are permitted to close together through the projection by which they are held.

2. The improved tuft-fastener for use in 5 brushes, consisting of a wire bent as described to present a series of tuft-holding projections.

3. The tuft-fastener for use in brushes, consisting of the sinuous strip having the projections adapted to enter the tuft-holes and bear 10 within the tufts, and having also the teeth or notches c^2 to engage the walls between the tuft-holes.

4. The improved brush consisting of the block or body provided with a series of holes,

the tufts inserted in said holes, and a sinuous 15 fastener having connected portions extending downward into the respective holes within the bight of the tufts, said portions having the openings c^4 , whereby the two sides of the tuft are permitted to close compactly together 20 above the fastening device.

In testimony whereof I hereunto set my hand, this 21st day of June, 1890, in the presence of two attesting witnesses.

MCCLINTOCK YOUNG.
